UNITED STATES PATENT OFFICE.

PETER B. AMSTUTZ, OF BLUFFTON, OHIO.

ROAD-WORKING MACHINE.

Application filed April 19, 1921. Serial No. 462,544.

To all whom it may concern:

Be it known that I, PETER B. AMSTUTZ, a citizen of the United States, residing at Bluffton, in the county of Allen and State of Ohio, have invented new and useful Improvements in Road-Working Machines, of which the following is a specification.

This invention relates to a road working machine and particularly to a machine of 10 this type adapted to operate on road surfaces covered with broken or crushed stone or the like, and consists in the preferred construction and arrangement of the several parts which will be more fully hereinafter 15 described and claimed.

As a general rule, when a roadway is covered with broken or crushed stone, ruts soon will be formed therein by vehicles following the same track, and if immediate and proper care of the road surface is not taken, 20 these ruts will shortly become an annoyance and inconvenience to general travel and defeat the desired imbedding of the broken or crushed stone over the entire road surface.

An object of the present invention is to 25 provide a road working machine having scraping devices readily controllable by adjusting means, to give proper shape to the covering of broken or crushed stone and 30 eliminate the ruts that may be formed, and thereby divert the travel from the same track and effect a thorough working in or 35 imbedding of the broken or crushed stone into the road bed. Another object of the invention is to provide a road working machine which will be comparatively simple and effective in its construction and operation, and easily operated and controlled.

These objects are attained by the mechanism 40 illustrated in the accompanying drawings and in which:—

Fig. 1 is a top plan view of a machine embodying the features of the invention.

Fig. 2 is a central longitudinal vertical 45 section of the machine.

Fig. 3 is a transverse vertical section taken on the line 3—3, Fig. 2.

Fig. 4 is a transverse vertical section taken on the line 4—4, Fig. 2.

The numeral 5 designates a frame of suitable construction and dimensions, it being proposed to use any kind of material in the formation of the frame. The frame 5 is 50 suitably mounted on transverse axle beams 6 and 7 respectively located below the front and rear extremities of the frame and hav-

ing road wheels 8 and 9 applied thereto, the front axle beam 6 and wheels 8 being mounted to turn, any preferred or approved devices being used for this purpose, and to 60 the front axle beam 6 a draft attachment 10 is connected and may be a tongue or a coupling device for securement to a tractor. Under the front extremity of the frame 5 and forming part of the front axle organization 65 is a bolster or beam 11 which is firmly attached to the frame and adjacent parts of the front axle organization. On the upper part of the forward extremity of the frame 5 a foot rest 12 is applied and at a suitable 70 distance in rear of the same is a seat 13. A platform 14 is secured to the rear side of the rear axle beam 7 and stands outwardly a suitable distance for the support of an operator or person who controls the several 75 mechanisms of the machine. It will be understood that the frame 5 may be braced and supplied with cross beams or analogous devices for application of the various mechanisms, as for instance, the cross beam 15 at 80 the rear of the frame for holding lever devices, which will be presently explained.

Between the front and rear axle beams 6 and 7 two scraper blades 16 and 17 are mounted and adapted to be adjusted at different 85 angles and also elevated above and lowered towards the road surface. The scraper blades 16 and 17 are preferably formed of steel of suitable thickness and are given a concavo-convex contour, as shown. These 90 blades or plates 16 and 17 are of such length that they will closely approach at their inner ends and also of a width to practically serve as a dragging means for the material or broken or crushed stone on the road surface with which the said blades engage and operate. The blades or plates 16 and 17 each have a pair of forwardly projecting carrier rods or analogous devices 18, each pair of rods first passing through attaching 95 clips 19 secured to the lower sides of adjusting beams 20, which are comparatively short so as to avoid interference at the inner extremities thereof during adjustment of the blades. The forward ends of each pair of 100 carrier rods 18 are formed with transverse openings 21 to loosely receive a connecting cross rod 22 loosely carried at opposite extremities in eyes or similar devices 23 attached to a short cross beam 24 having an 105 eye 25 secured to its front side at the center thereof and engaged by an eye-bolt 26 pro-

jecting rearwardly from the beam 11. Depending from the inner portion of each of the side beams of the frame 5 is a hanger 27 having a lower hooked end to engage under and intermediately sustain the adjacent rod 22. The beams 24 are loosely connected in the manner just explained through the medium of the eyes 25 to permit these beams to be rocked or canted to correspondingly adjust the blades 16 and 17, and in addition to this adjustment the blades through the carrier rods 18 may also have a hinge action. By connecting the beams 24 to the beam 11 through the medium of the eyes 25 and 26, stiffness of action during the adjustment of the carrier rods 18 and the blades or plates 16 and 17 is avoided, and through the devices which will be hereinafter specified the blades are rendered sensitive to varying adjustments in scraping the road covering of broken or crushed stone or any other material with which the blades may be brought into engagement.

The rear adjusting beams 20 are suspended below the frame 5 through the medium of angle plates or strips 27 secured thereto and having outer upwardly projecting angular extremities 28 movably attached by links 29 to bell crank levers 30 pivoted against the inner sides of the side beams of the frame 5 and having their upper extremities connected by rods 31 to operating levers 32 having suitable catch means working in conjunction with adjustment-retaining devices or toothed segments 33. The angle plates or strips 27 are mounted on the beams 20 in such manner as to have a slight swinging movement, the means employed to permit this latter movement for each of the beams being a single fastening means 34 being inserted through the centers thereof and into each of the said beams 20, as shown by Fig. 1, in order to prevent stiffness of these angle plates during the adjustment, and particularly when the blades 16 and 17 and their carrier rods 18 together with the beams 20 are unitedly shifted laterally or in opposite sidewise directions. The inner extremities of the angle plates 27 are upturned, as at 35 and 36, and connected to these two inner extremities is a link 37, whereby the beams 20 and the blades 16 and 17 and rods 18 will be held apart a uniform distance in accordance with a predetermined adjustment and also shifted as a unit in lateral directions. The means for shifting the beams 20 and the blades 16 and 17 together with the carrier rods 18 in opposite sidewise directions consists of a connecting rod 38 attached to the one upward angular projection 36 at the inner end of one of the angle plates 27 and also attached to a horizontal bell crank lever 38^a fulcrumed against the lower side of the adjacent side beam of the frame 5. An actuating connecting rod 39 is also at-

tached to the bell crank lever 38^a and to an operating lever 40 at one side of the rear of the frame and held on the cross beam 15, which also supports the segments 33. Adjacent the lever 40 is a toothed segment 41 with which a suitable catch dog 42^a carried by the lever 40 cooperates to maintain the lateral or sidewise adjustment of the blades as may be desired.

A U-shaped bracket 42 is secured to the beam 11 and has the arms thereof extending upwardly, and to these arms bell crank levers 43 and 44 are pivotally attached. To the lower arms of these bell crank levers 43 and 44 links 45 and 46 extend downwardly and are movably connected to the inner extremities of the beams 24 to which the forward ends of the carrier rods 18 are attached by the cross rods 22. To the upper arms of the bell crank levers 43 and 44 connecting rods 47 and 48 are respectively attached and also movably secured at their rear ends to levers 49 and 50 supported by and adjacent to toothed segments 51 and 52 and provided with suitable catches to interlock with said segments. The segments 51 and 52 are mounted on the cross beam 52 and the rear end of the frame to which the axle beam 7 is attached. The levers 49 and 50 are shiftable forwardly and rearwardly to correspondingly shift the connecting rods 47 and 48 and operate the bell crank levers 43 and 44 to lower or raise the inner ends of the beams 24, which readily swing, in view of the eye-bolt connections 25 and 26 therefor, relatively to the beam 11. By swinging the beams 24 in the manner just explained, the carrier rods 18 and blades 16 and 17 are correspondingly adjusted at angles to the road surface, and whereby the crown of the road may be given the desired angle or pitch.

Depending from the rear axle beam 7 are a pair of hangers 53, as clearly shown by Fig. 3, and movably attached to these hangers is a rear leveler 54 having arms 55 through which and the lower extremities of the hangers extends a pintle or rod 56. The leveler 54 is of sufficient weight to perform the function for which it has been devised and applied to the machine, namely, to level the ridge which is sometimes produced by the scraper blades, or to even the surface covering of the roadway.

From the foregoing the operation of the machine will be understood, and when it is desired to remove the ruts from a roadway covering of broken or crushed stone, the blades 16 and 17 are lowered to engage the covering and penetrate the latter to such depth as to effect an elimination of the ruts, and, furthermore, the blades may be shifted very quickly at intervals to follow an irregular track, or said blades when shifted may remain in shifted position to

- operate on opposite side portions of the covering of the roadway. Moreover, by operating the devices hereinbefore specified, the blades 16 and 17 can also be disposed 5 to have their inner lower corners elevated or their outer corners lowered, or vice versa, in accordance with the work to be performed, or to produce the desired shape of the road surface. The leveler 54 following behind 10 the blades 16 and 17 will insure a flattening of any ridge that may be produced by the blades 16 and 17. It will be seen that all of the adjusting levers are located adjacent the platform 14 within easy reaching distance 15 of an operator and may be quickly manipulated to dispose the blades 16 and 17 as may be required during the operation of working the covering of the road bed. The scraper blades are so mounted and have 20 such adjustment that both the outside of the road covering as well as the center portion thereof may be easily reached and worked, and the ruts will be quickly filled in by the action of the scraper blades and 25 the surface of the road covering given a level and properly pitched form. The parts may also be modified in proportions and general dimensions to adapt the machine to various kinds of work, as for instance, by 30 lengthening the two connecting rods between the scraper blades and permitting a greater lateral shifting action of the said blades, the latter may be practically used to fill a tile ditch or level up a land furrow. 35 In addition to the uses of the machine as hereinbefore specified, it will be understood that it can be employed for any other work to which it may be adapted.
- What is claimed as new is:
- 40 1. In a road working machine of the class specified, the combination of a frame, scraping blades movably supported from the frame for vertical adjustment and also free sidewise movement as a unit, suspending 45 beams movable applied over and connected to portions of the blades and having means for maintaining them apart a predetermined distance and also for shifting them as a unit in lateral directions, canting beams attached to the blades and also movably connected to a part of the frame, and lever devices and connections for vertically adjusting and laterally shifting the blades and 50 operably attached to said beams.
- 55 2. In a road working machine of the class specified, a frame, scraper blades having forwardly projecting carrier rods, suspending beams connected to the carrier rods adjacent to the blades, canting beams disposed 60 under the front extremity of the frame and movably attached to a part of the latter, the carrier rods being movably connected to the canting beams, each blade having a suspending and a canting beam independent 65 of the like devices of the remaining blade, and lever devices and connections attached to the beams for adjusting the latter vertically, laterally and at angles relatively to a road surface.
3. In a road working machine of the class 70 specified, a frame, blades disposed under the frame and having forwardly projecting carrier devices, an individually movable suspending beam to which the carrier devices of each blade are attached adjacent to 75 the blade, independent canting beams to which the front ends of the carrier devices of the blades are hinged, means for movably connecting the canting beams to a part of the frame, means for connecting the suspending beams for unitary lateral adjustment, the blades being also movable vertically and at angles with relation to a road surface, and lever and connecting devices attached to the beams for adjusting the 80 latter.
4. In a road working machine of the class 85 specified, a frame having running gear including axle devices and a rear platform, blades mounted under the frame and having 90 devices attached thereto for raising and lowering them and also canting the same at different angles and for unitedly adjusting the blades laterally, operating levers and connections for the blades located adjacent to 95 the said platform for control and actuation by an operator standing on the platform, and a rear downwardly inclined flat leveler blade pivotally connected to a part of the rear portion of the running gear for spreading 100 the material worked up by the blades under the frame in advance of the leveler.
5. In a road working machine of the class 105 specified, a frame having running gear including axle devices and a rear platform, blades mounted under the frame and having 110 devices attached thereto for raising and lowering them and also canting the same at different angles and for unitedly adjusting the blades laterally, and operating levers and connections for the blades located adjacent to 115 the said platform for control and actuation by an operator standing on the platform.
6. In a road working machine of the class 120 specified, the combination of a frame having running gear including axle devices and road wheels, a beam extending across under the front extremity of the frame in connection with the front axle device, blades 125 mounted under the frame and having forwardly projecting carrier devices, canting beams having hinge connections to the said beam located at the centers of the canting beams, the canting beams being provided with means for hinging the front ends of the carrier devices thereto, independent suspending beams connected to the carrier devices adjacent to the blades and also having means movably connecting them, and 130

lever devices and connections attached to the inner ends of the canting beams and to the suspending beams for adjusting the blades at relative angles, vertically and laterally, the suspending beams being tied for unitary movement.

In testimony whereof I have hereunto set

my hand in presence of two subscribing witnesses.
